(57) **CLAIM**

(21) Appl. No.: **29/133,116**

The ornamental design for a coin sorting and calculating machine, as shown.

(22) Filed: **Nov. 22, 2000**

DESCRIPTION

(30) **Foreign Application Priority Data**

May 25, 2000 (SE) 00-1015

FIG. 1 is a front perspective view of a coin sorting and calculating machine.

(51) LOC (7) Cl. **18-01**

FIG. 2 is a rear perspective view thereof.

(52) U.S. Cl. **D18/3.1**

FIG. 3 is a front elevation view thereof.

(58) Field of Search D18/3.1-3.3; D99/28, D99/38; 453/3, 18, 63; 194/217

FIG. 4 is a bottom plan view thereof.

(56) **References Cited**

FIG. 5 is a top plan view thereof.

U.S. PATENT DOCUMENTS

FIG. 6 is a left elevation side view thereof.

D. 359,152 * 6/1995 Adams et al. D18/3.1
5,429,551 * 7/1995 Uecker et al. 453/18

FIG. 7 is a right elevation side view thereof; and,

FIG. 8 is a rear elevation view thereof.

FIGS. 3-8 are drawn on a reduced scale.
